SPECIAL PACKAGE

Russell Stover, Kansas City, Mo.

Application May 28, 1934, Serial No. 727,908

3 Claims. (Cl. 206—44)

My invention relates to special packages and more particularly to a special package of confections.

It has long been the practice of confectioners to pack their confections in boxes which have been sealed so that a prospective purchaser cannot view the merchandise he is about to buy. Then, too, when a box of candy is opened, a layer of chocolates and bonbons is presented, which, to the eyes of most persons, look more or less alike so that it is difficult or impossible to choose a particular piece as desired. Frequently, people have pet likes and dislikes in connection with candy. It has been known that a piece of candy will be chosen from a box and discarded after the first bite, because it happens to be one which does not appeal to the gustatory taste of the person.

One object of my invention is to provide a box of confections which can be inspected while retaining the contents of the package in a sealed condition.

Another object of my invention is to provide a means for enabling one to choose his favorite piece with accuracy and precision.

Other and further objects of my invention will appear from the following description.

In the accompanying drawing which forms part of the instant specification and is to be read in conjunction therewith and in which like reference numerals are used to indicate like parts in the various views;

Figure 1 is a perspective view of a package of my invention.

Figure 2 is a sectional view taken through a package embodying one mode of carrying out my invention.

Figure 3 is an enlarged plan view of a portion of a package of my invention.

In general, my invention contemplates the provision of a box provided with a compartmented bottom adapted to receive various pieces of confection and hold them in more or less predetermined position. These compartments may be disposed so that the box may be used with or without compartments. The box is provided with a transparent covering. This transparent covering may be of any suitable nature, such as of viscose or cellulose acetate and more particularly of a material sold under the trade name of "Cellophane". The transparent sheet is well secured to one edge of the box so as to be always attached thereto and to act in the nature of a hinged cover. Upon the sheet are provided indicia or other suitable indicating means such as legends or the

like to identify the particular piece of confection which is held in place directly thereunder.

More particularly referring now to the drawing, a box or tray 1 is provided with a bottom member 2, which may be formed integral with the bottom of the box 1 or separately as shown in Figure 2. The member 2 is provided with longitudinal and transverse raised portions 3, forming compartments 4 as can readily be seen by reference to Figures 1 and 3. Within the compartments are placed confections 5, seated in the usual paper cups 6. It is to be understood, of course, that the paper cups need not be used unless desired.

Permanently secured to one side of the box 1 as at 7 in Figure 2 is a sheet of flexible transparent material 8. The transparent material is slightly larger than the box 1 so that it forms a depending flangelike portion 9. The depending portion 9 may or may not be provided with a longitudinal bead 10 formed by a piece of string or the like, to which is attached a loop 11 which will enable the "Cellophane" cover sheet 8 to be opened. The transparent cover furnishes protection for the goods after the box lid has been removed and, at the same time, exposes the contents. That portion of the cover 8 which is secured along the side 1 is permanently secured by strong adhesive or the like. The peripheral part of the rest of the cover sheet 8 is more or less lightly secured to the walls of the box 1 so that it may be readily opened by means of loop 11. Upon the cover sheet 8 appear various indicia 12 to indicate the character of the confection housed in the compartments 4 directly under the sheet. It is to be understood, of course, that a number of trays may be put in a single box, or the box may act as a receptacle and be provided with a separate cover member as is customary in candy boxes.

In operation, it will be readily understood that the cover of box 1 may be removed, thus exposing the contents to view, while at the same time protecting them from exposure to dust, moisture, and the like. At the same time, a prospective purchaser will be advised of the exact nature of the contents of the box. When it is desired to eat the candy, the "Cellophane" protecting sheet 8 which carries the indicating means 12 is lifted by means of loop 11. The sheet being permanently secured to one side of the box acts as a hinged cover and, at the same time, as a grille, enabling each particular piece to be picked out at will. The ribs 3 hold the candy in a predetermined position so that, as a piece is eaten, the

other pieces will not move out of position from beneath the indicating means. It is to be understood, of course, that any suitable means for holding the candies in position may be employed. For example, the cups 6 may be secured to the bottom of the box by means of an adhesive or the like so that the paper cups will serve to hold the candies in predetermined position.

It will be seen that I have accomplished the objects of my invention. I have provided a novel and handy package which will enable the contents of a box of candy to be inspected before its purchase, a thing hitherto not possible, while, at the same time, protecting the candy. The indicating means enables a consumer to choose his favorite piece.

Having thus described my invention, what I claim is:

1. In a package of confections, a receptacle, a cover for said receptacle formed of transparent flexible material, assorted confections each held in a relatively fixed location in said receptacle

and indicia on said cover for indicating each of the species of confection positioned beneath said indicia within the receptacle, and means for securing one edge of said cover to said receptacle whereby it acts in the nature of a hinged cover.

2. In a package of confections, a receptacle, a cover for said receptacle having a transparent face said cover constructed for removing and replacement, assorted confections held in a substantially fixed location beneath said transparent cover, indicia on the cover adjacent said confections and identifying by location the character of the same.

3. In a package of confections, a receptacle, a cover for said receptacle constructed for removal and having a transparent face, assorted confections held in a substantially fixed location beneath the transparent cover, indicia on the cover adjacent said confections and identifying by location the character of the same.

RUSSELL STOVER.
